UNITED STATES PATENT OFFICE

139,432

DESIGN FOR A HELICOPTER

William B. Stout, Pontiac, Mich., assignor to Consolidated Vultee Aircraft Corporation, San Diego, Calif., a corporation of Delaware

Application April 13, 1944, Serial No. 113,237

Term of patent 14 years

(Cl. D71—1)

To all whom it may concern:

Be it known that I, William B. Stout, a citizen of the United States, residing at Pontiac, in the county of Oakland and State of Michigan, have invented a new, original, and ornamental Design for a Helicopter, of which the following is a specification, reference being had to the accompanying drawings, forming a part thereof.

In the drawings:

Figure 1 is a top plan view of a helicopter showing my new design;

Figure 2 is a side elevational view;

Figure 3 is a front elevational view; and

Figure 4 is a bottom plan view.

I claim:

The ornamental design for a helicopter, substantially as shown.

WILLIAM B. STOUT.
